UNITED STATES PATENT OFFICE

162,386

GAME BOARD OR SIMILAR ARTICLE

James W. Connolly, Boston, Mass.

Application October 11, 1949, Serial No. 5,428

Term of patent 7 years

(Cl. D34—5)

To all whom it may concern:

Be it known that I, James W. Connolly, a citizen of the United States, residing at Boston, in the county of Suffolk, in the Commonwealth of Massachusetts, have invented a new, original, and ornamental Design for a Game Board or Similar Article, of which the following is a specification, reference being had to the accompanying drawing, forming a part thereof, in which:

The design on the drawing shows surface representations.

I claim:

The ornamental design for a game board, or similar article, substantially as shown and described.

JAMES W. CONNOLLY.
